ADJUSTABLE STOP MECHANISM

Harold A. Strickland, Jr., Detroit, Mich., assignor
to Budd Wheel Company, Philadelphia, Pa., a
corporation of Pennsylvania

Application September 1, 1943, Serial No. 500,773

5 Claims. (Cl. 263—6)

This invention relates to induction furnaces and more particularly to adjustment mechanism for maintaining the workpiece within the heating chamber of the furnace at a predetermined stop point.

In my copending application, Serial No. 384,503, filed March 21, 1941, I have disclosed an electric furnace machine in which utilization is made up of a tubular furnace having open front and rear ends, there being provided a stop at the rear end to limit the movement of the workpiece through the furnace heating chamber. In this application the general inventive idea of the copending application is retained but certain practical improvements are incorporated. For example in the original arrangement access to the stop holding means required partial dismantling of the furnace whereas in the present application the stop may be adjusted from a point external to the furnace casing. Accordingly, the primary object of the present invention is to provide means whereby the workpiece stop may be adjustably positioned with reference to the furnace chamber. Still another object of the invention is to provide a stop for a furnace work-piece which may be adjusted from a point external to the furnace casing. An object also is to provide a stop which has universal adjustability along the axis movement of the stop. Further objects identified with detailed structure of the adjustment mechanism will appear on consideration of the following description and related drawing, in which:

Fig. 1 is a view partly in section of a portion of the furnace illustrating the relationship of furnace chamber stop and stop adjusting means:

Fig. 2 is a detail showing a side view of the adjusting mechanism, and:

Fig. 3 is a front view of the adjusting member.

The furnace generally indicated by the numeral 10 is provided with a casing 11, a ventilating screen 12, a base plate 13 and an end plate 14, the latter closing the furnace chamber 15 and separating it from the instrument chamber 16. The furnace generally indicated by the numeral 17 has a tubular construction and comprises an induction heating coil 18 having an overlying asbestos bodied coat 19 and inner layers of glass, mica or mica containing material 20. Also within the mica layers are sections of refractory insulation brick 21 supported by rails not shown, to which are attached guide plates 22 for supporting the workpiece. External supporting rails 23 are utilized to maintain the insulation brick and brick supporting rails within the heat-

ing chamber. The furnace unit is supported within the casing 11 by means of C-brackets 24, one of which is shown in Fig. 1, the same consisting of a base section 25 to which is attached integrally the C-section 26 extending partially around and above the furnace. The C-section is provided with adjustable contact screw heads 27 and 28, the latter being of U-shape and yieldably associated with the bracket 26 through the coil 10 spring 29.

The stop or gauge 30 is of tubular construction and is adapted for axial movement along the axis of the furnace chamber through the opening 31 formed centrally in the furnace casing end plate 14. A ring of metal 32 is preferably added to the end of the stop, adjacent the furnace, so as to give added diameter and contact area for engagement with the workpiece. The stop 30 is adapted to be supported upon the bracket 33 bolted to the end plate 14, this bracket being of approximately triangular shape in plan as shown in Figure 3, with a side projection 34 at one edge having a curved central area 35 for reception of the curved stop tube, which is adapted to lie therein as shown in Figure 3. The support section 34 of the bracket is of sufficient width to cover a substantial section of the stop tube as shown in Figure 1. The edge of the bracket 33 from which the supporting extension 34 extends is also provided with 30 outwardly extending lugs 36 which are similar and in alignment and provided with pivot receiving apertures for the reception of the pivot pin 37. The holding or locking member 38 is mounted on the pivot pin 37 between the lugs 36 and is adapted for pivotal movement in a plane perpendicular to the furnace casing end plate 14. By the term "locking" is meant fixing or holding with reference to the position of the slideable stop. As shown in Figures 1 and 2 this locking member 40 38 is vertically positioned and directly overlies the tubular stop 30 which is slideable between the base of the locking member 38 and the bracket 45 guide 34.

In the construction shown, the locking member 38 is triangular in shape, having a thickened rear edge 39, the upper end of which is adapted to make contact with the end of an adjusting screw 40, the latter being mounted on the end plate 14 in an opening therethrough and having a lock 50 nut 41 to adjustably secure the screw in any desired set position. The forward edge of the triangular locking member 38 is relatively thin, but terminates at its lower end at the conjunction with the base of the triangle in a thickened head 55 42. This head extends transversely in relation to

the plane of the locking member 38, and in relation also to the stop tube. The head also directly overlies the stop tube.

The base of the triangular locking member is formed with a square notch as shown in Figure 2, part of the notch being formed in the web of locking member 38 at 43 and part in the head 42 at the point 44. This notched opening is adapted to receive, by insertion on the side of the locking member the square contact bar 45 which is of metal relatively harder than that of the metal of the locking plate. After insertion the bar is welded or brazed to the metal of the locking member as indicated by the numeral 46, it being observed that when subjected to pressure the bar will not place any strain on the welded joint.

The operation of the mechanism is now apparent. On release of the lock nut 41 and the retracting screw 40, the lock bar 45 may be elevated to a point displaced from the tubular stop 30. Thereupon the tube 30 may readily be shifted axially to move the stop head 32 in relation to the furnace to such a point as may be found desirable for the particular workpiece being heated. At the desired point of adjustment, the screw 40 is moved to compress the bar 45 and which being of relatively harder metal will engage and depress the softer metal of the stop tube. The lock nut 41 is then tightened and the stop tube is held securely in place with adequate resistance to the impact of the workpiece against the stop head 32.

Associated with the stop tube 30 is an ejector or pushout rod 47 which is adapted to lie within the tubular space of the stop tube extending the full length of the same and in heat treating position extending a substantial distance to the rear thereof. The ejector rod is preferably hollow to permit cooling by the circulation of a coolant through the connecting tubes 48 as shown in Fig. 1. Preferably the furnace end of the ejector rod is of refractory material, so as to withstand high temperatures encountered at this point. Secured to the ejector rod is a collar 49 which may be adjustable along the length of the rod and which is adapted to contact with the tip 50 of a bell crank 51 pivoted at 52 on a bracket 53 fastened to the exterior lower side of the furnace end plate 14. The bell crank includes an arm 54 the end of which is apertured to receive the end of a coil spring 55, the upper end of which engages the second bracket 56 positioned above the level of the stop tube 30. The outward end of bracket 56 is adapted to support pivotally the cylinder 57 of a fluid pressure unit including a cylinder and piston the piston extending as a rod 58 to a pivot 59 secured to the bracket arm 54 intermediate the pivot 52 and spring engaging end thereof. Fluid under pressure is introduced through the pipe 59 which tends to force the piston downwardly and thereby turning the bell crank so as to force the contact end 50 thereof into engagement with the ejector rod collar 49 and move the ejector rod inwardly to engage and eject a workpiece from the furnace chamber. This ejecting action of the bell crank 51 is against the tension of the spring 55, so that when the fluid pressure is released in the cylinder 57, the spring pivots the bell crank 51 rearwardly thereby permitting free outward sliding movement of the ejector rod on insertion of a new workpiece within the heating chamber.

It is of importance to note that not only is the stop tube 30 axially adjustable with reference

to the furnace 19, but that this adjustment is axially universal, there being no fixed series of points to which adjustment must be made as by a stepped stop mechanism. Furthermore it is pointed out that complete adjustment of the stop or gauge may be made at points exterior to the furnace casing. This is of considerable importance in practice since the necessity of removing the casing 11 for access to the interior of the casing for purposes of adjustment of the stop tube involves not only time delay but considerable nuisance. In accordance with the described mechanism, it is necessary only that the operator determine by inspection of the bar or other workpiece the extent to which adjustment should be made in order to obtain the desired heat treatment of the inner end of the bar. Thereupon the operator may release the locking nut 41 of the locking screw and make the required adjustment and then lock the member 38 in its new position, this adjusting operation taking place at a point exterior to the furnace casing. It is further noted also that the means of adjustment described do not interfere in any way with the action and movement of the ejector rod for normal adjustments. In cases of large adjustments the collar 49 must be moved along rod 47.

Modifications of the invention may be made, the scope of the invention being comprehended in the following claims.

What is claimed is:

1. In heating apparatus, a furnace chamber having an opening through which a workpiece is movable, a slidable stop for limiting the movement of the workpiece through said opening and means for locking said stop at variable points with reference to said chamber, said locking means comprising a frictional element pivotally mounted adjacent said stop and means imparting pivotal movement to said frictional element to and from said stop whereby the stop may, at will, fixedly hold in any desired position relative to the furnace chamber.

2. In heating apparatus a furnace chamber within said casing having an opening therein through which a workpiece is movable, a stop for limiting movement of the workpiece in relation to said opening and means for locking said stop in any desired position, said locking means being operable at a point external to the furnace casing.

3. In heating apparatus, a furnace casing and a tubular furnace chamber having an opening through which a workpiece is movable, a stop axially aligned with said furnace chamber and in movable relation thereto, an ejector rod positioned adjacent said stop and axially movable relative thereto and separate means external to said casing for adjusting the axial position of either stop or ejector rod.

4. In heating apparatus a furnace casing and a tubular furnace chamber having an opening through which a workpiece is movable, a tubular stop axially aligned with said furnace chamber and in movable relation thereto, an ejector rod positioned within said stop and axially movable relative thereto and separate means external to said casing for adjusting the axial position of either stop or ejector rod, including means for locking the stop in any desired position.

5. In adjustment mechanism for heating apparatus, a support plate, a bracket having a curvilinear curve attached to said plate adjacent an

aperture formed therein, a stop tube slidable within said plate aperture and in said bracket curve, said tube extending through said aperture to the side opposite of the bracket whereby the same may be adjusted with reference to the plate and frictional holding means for locking said tube in fixed position relative to the plate, said

holding means comprising a contact bar, and bar holding means pivotally mounted on said bracket for moving said bar into and out of engagement with said stop tube and means supported by said plate for engaging the pivotal member for forcing the bar into contact with the tube.
